MANIFOLDING DEVICE

Arthur A. Johnson, Bridgeport, Conn., assignor to
 Autographic Register Company, Hoboken, N. J.,
 a corporation of New Jersey

Application April 20, 1938, Serial No. 203,008

24 Claims. (Cl. 197—133)

This invention relates to manifolding devices, and, more particularly, to improvements in mechanisms for feeding a plurality of superposed continuous strips of paper as in a typewriter.

Heretofore it was proposed to provide the continuous strips with physical alterations, usually in the form of apertures, which, in cooperation with the feeding disks, would cause the feeding operation of each individual strip to cease when the feeding disk entered the aperture therein. This not only caused the strips to stop feeding, but also permitted them to move into alignment with each other either by the tendency of the feeding disk engaging the margin of the aperture to advance the strip, or by reason of some provision being made in the pile of strips for causing them to reregister. Such a feed is disclosed in the patent to Shoup and Oliver, No. 1,396,070, November 8, 1921.

It has been proposed more recently to feed a pile of continuous record strips with and around the platen of a typewriting machine by a feeding device having these characteristics.

With these prior proposals in which the feeding means operates idly while the feeding disks are in their apertures, when the paper strips are thereby stopped and aligned, some operation must be performed (usually manually) whereby the strips are engaged and fed at unapertured portions thereof. For this purpose, such machines are usually provided with a starting device, usually in the form of an auxiliary feed roller, normally out of operation but brought into operation when desired and engaging the paper strips at a point offset from the apertures.

When superposed paper strips having feed-arresting, form-registering apertures are employed in a manifolding register, the feeding operation is continuous until one form-length is fed, i. e., until the next set of feed-arresting, form-registering apertures reach the pressure disks. To restart the strips under such conditions, I have provided, as in my Patent No. 1,815,063, granted July 21, 1931, an automatic starting device which becomes capable of restarting the paper within a predetermined time after the continuous feeding operation has ceased, thereby eliminating the necessity of the operator performing any manual operation to cause the paper to restart upon the next operation of the feeding mechanism.

When the paper strips having feed-arresting, form-registering apertures and cooperating pressure disks are employed in a typewriter, however, the feeding mechanism, being intermittently operated to space the paper line-by-line, cannot

be again started as a result of cessation of movement of the feeding mechanism, because this would cause the starting mechanism to be operative practically all of the time and the paper strips would not stop when the feeding disks entered the apertures.

It is an object of this invention to automatically restart the feeding of the paper strips, or at least to place the mechanism in position to restart even though the feeding mechanism is operated intermittently.

In the broader aspects of this invention, this may be accomplished in various ways. In the form of the invention herein disclosed, this is done by initiating the operation of the starting mechanism as a result of the cessation of advancing movement of the paper strips, and the arrangement is preferably such that, after the strips have stopped, a predetermined number of idle operations of the feeding means occurs before the operation of the starting mechanism is initiated and the paper restarted so as to give an opportunity for the paper strips to be brought into registration. With the device of the present invention, because the idle operations are limited and definite in number, it is possible to employ the self-stopping and aligning frictionally fed superposed strips in a remotely controlled device, as in the case of a teletypewriter, in which the paper strips in the sending and receiving machines should be advanced in synchronism.

Such devices are operated at the receiving end without the supervision of an operator and entirely automatically, and hence, if the restarting mechanism were not automatically operated, according to a predetermined plan, this advantageous feed mechanism could not be employed. Such remote control typewriting machines, especially when operating on printed paper strips, have heretofore been provided with positive acting feeding means comprising pin wheels engaging longitudinal rows of apertures in the paper strips.

The present invention, by providing for the frictional feeding of the strips with registration being maintained by the feed-arresting, form-registering apertures and providing means for automatically starting the feeding operation of the strips after a predetermined number of idle feeding operations have been performed, obviates the need of having the sprocket feed with its unenhancing rows of pin holes.

In the form of the invention herein disclosed, a feeler roller is caused to engage the paper and 55 to rotate when the paper advances, but to re-

main stationary when the paper ceases to advance. This feeler roller is so organized and mechanically related to one or both feeding disks, which rotate when the feeding mechanism is operated whether or not the paper is advancing, that the relative movement between the feeler roller and the feeding disk causes the paper-starting device to be brought into operation. The mechanism is so arranged that when the starting operation has been completed, the feeler roller and feeding disk reestablish their normal relation and continue to rotate coordinate until the paper strips again stop.

With this kind of device, no change need be made in the mechanism of the device to accommodate it to forms of different length, and any machine may handle forms of any length.

Other features and advantages will herein-after appear.

In the drawings which show by way of example several forms of this invention—

Figure 1 shows a longitudinal sectional view of the feeding mechanism.

Fig. 2 shows a plan view of the same.

Fig. 3 shows a detailed plan view of the feeding mechanism being partly in section.

Fig. 4 shows a detailed plan view of the feeding mechanism, a part of which is broken away.

Fig. 5 shows a detail front elevation of the detent release means.

Fig. 6 is a view taken along line 6—6 of Fig. 3 and shows a detail view of the detent in stopped relation with the notch of the starter roller.

Fig. 7 is a detail view taken along the line 7—7 of Fig. 4, showing the detent raised from the notch in the starter roller.

Fig. 8 is similar to Fig. 7, showing the detent resting on the contacting surface of the starter roller during rotation thereof.

Fig. 9 shows a longitudinal section through the feeding means of another form of the invention.

Fig. 10 shows a plan view of the device shown in Fig. 9.

The present invention is illustrated as adapted to the invention described in copending application Serial No. 187,044, which discloses means for feeding and maintaining registration of manifolding strips when used in a typewriting machine.

As shown in the accompanying drawings, the invention is applied to a front-strike typewriting machine having a cylindrical platen 10 mounted in a carriage frame 11. The usual feed rollers 12, which are adapted to press worksheet strips against the platen, are dropped in inoperative position when the device of the present invention is used. The platen is rotated line-by-line by a line spacing mechanism including a ratchet wheel 13 mounted on the shaft 14 carrying the platen and is rotatably mounted in the carriage frame 11.

Paper sheets or strips are guided to the platen by a paper table 15. An apron 16, disposed adjacent the platen, causes the paper to follow the curvature of the platen and lie close thereto at the line of writing 17 where type bars 18 strike upon the platen.

The machine has a bail including side arms 21 which usually supports auxiliary presser rollers engaging the work in advance of the writing line. The arms are locked down by latches 22 pivoted at 23 on the carriage. The feeding mechanism of the present invention is mounted on the bail in place on the auxiliary roller.

The manifolding material used with the present invention comprises a plurality of record strips 24 having forms 25 printed thereon and having interleaved therewith transfer strips or continuous carbon sheets. The strips are provided with transverse lines of weakness 27 whereby the strips of the pile can be severed to form sheet lengths.

The pile of strips may be held together in registration by a staple 28 disposed preferably on each weakened tear line 27.

As described in said copending application, the paper tends to creep when being moved around the curved platen, and, to avoid the accumulating of the creep, the pile is provided with physical alterations, and feeding means, which are relatively narrow disks or rollers, are adapted to enter the aperture or physical alterations and relieve the pile of strips of the feeding pressure so that the creep accumulated therein can be dissipated.

The physical alterations may be of any shape. In the illustrated form, however, they are made as notches 31 disposed in pairs along the lateral margins of the pile. The pile of strips is advanced by a pair of feeding disks 32a, 32b engaging the pile, one at each side of the machine, and located in longitudinal alignment with the notches 31. The feeding disks may be of any suitable material capable of frictionally feeding the strips and are carried by a rod 33 mounted in a pair of arms 34 which are pivoted at 35 on the arms 21 in place of the usual auxiliary roller rod. The rod is secured against rotation by screws 33a threaded through the arms into the ends thereof, see Fig. 3.

The arms 34 extend rearwardly and are provided with springs 36 connected to a bar 37 on the machine so that the rollers are yieldingly pressed against the platen and the pile of papers carried thereby.

To keep the bail arms 21 from rising as a result of the pressure of the rollers 32a, 32b against the platen, they are provided with a pin 38 engaging a notch in the locking arms 22 referred to above.

After the manifolding pile has been fed around the platen and under the pressure disks 32a, 32b, the rotary movement of the platen will cause the pile of strips to advance line-by-line with the platen until notches 31 reach the bite of the rollers 32a, 32b, at which time the rollers enter the notches and relieve the pile of strips from feeding pressure. The strips are thus enabled to shift to relieve the bunch formed therein.

In this position, the movement of the platen will rotate the feed rollers but will not, of course, advance the strips.

To insure against the platen inadvertently advancing the pile of strips while the disks 32a, 32b are located in the notches 31, a drag plate 38 is located between the platen and the pile of strips and between the writing point and the bite of the disks. The plate 38, which separates the pile of strips so that rotation of the platen will not advance the strips, is secured to arms 41 carried on the pins 38 of the bail arms 21. The plate 38 is provided with lateral guides 42 which cooperate with lateral guides 42a on the paper table to assist in keeping the pile in proper position on the platen with the notches 31 longitudinally aligned with the feeding disks 32a, 32b.

Inasmuch as the feed means will be rendered inoperative at each form-length interval, some

means for restarting the feed means must be used. Usually an operator applies sufficient manual pressure, as with her finger, on the pile at a point of engagement with the platen whereby the operation of the platen will carry the pile a sufficient distance for the rollers 32a, 32b to again engage the pile and frictionally feed the pile another form length.

The frictional feed of the prior type could not be used with machines operating at remote points without the supervision of an operator, as in the Teletype machine. An object of the present invention is to overcome this difficulty and this is done by providing means for automatically restarting the feeding operations after a predetermined number of idle feeding operations have been performed. This will enable the operator at the sending end to automatically restart the feed means of the receiving machine through a predetermined number of operations of the line spacing mechanism, corresponding to the number of idle operations of the line spacing mechanism at the sending machine, which it is necessary to perform to start the paper at the sender.

The restarting of the feeding mechanism may be accomplished in many ways. The present invention utilizes the cessation of movement of the strip during the idle operations of the feed mechanism to initiate the restarting mechanism. This is accomplished by providing a feeler mechanism which engages the paper and is driven by the advancement thereof. The feeler mechanism which is driven by the strip will move synchronously with the feeding mechanism during normal feeding of the form. However, upon cessation of the strip to advance during the operation of the feeding means, the feeler mechanism will remain stationary while the feeding mechanism continues to operate. The feeding means and feeler mechanism are interconnected so that the differential movement between them, occurring when the feeding means is operated in inoperative feeding relation with the strip, will actuate a trip device for initiating operation of the starter mechanism for restarting a strip and moving it until the feed mechanism again controls the advancement of the strip.

In the broader aspects of the invention, a feeler mechanism for detecting cessation of movement of the paper, while the feeding means is operating in inoperative advancing relation with the paper, is utilized to automatically control the restarting of the advancement of the strip by the feeding means.

In the form of the invention herein disclosed, there is a starter roller 45 having a pair of contacting surfaces 45a and 45b and mounted on the rod 33 to cooperate with the platen at a point spaced from the notches in the strips. To drive the starter roller 45, the feed roller 32a is secured to a sleeve 47 which is rotatably mounted on the rod and held in adjusted position by a pair of collars 48 and 49 secured to the rod at each end of the sleeve by set screws. The sleeve 47 extends toward the middle of the strip and the starter roller is mounted thereon to engage the strips at a point spaced from the notches. One end abuts a collar 50 and is held thereagainst by a spring 51 surrounding the sleeve and disposed adjacent the other end thereof.

One end of the spring contacts a collar 52 adjustably secured to the sleeve 47 and the other end presses a friction washer 53 or the like against the end of the starter roller. The pressure of

the spring can be adjusted by moving the collar 52 to regulate the friction drive. Thus, when the feed roller rotates with the platen, the starter roller will tend to rotate therewith.

However, during the feeding of a form, the starter roller is held against such rotation until such time as it should operate to restart the strips. The starting mechanism is then rendered operative to move the strips a sufficient distance to enable the rollers 32a, 32b to engage the edges of the strip and again resume the advancement of the strips.

The starter roller can be held against rotating with the feed roller by any desired means. In the preferred form of the invention, the contacting surfaces 45a, 45b are cut away as shown in Figs. 6 to 8 at 54 and 55 to form opposed flat sides provided with notches to be engaged by a detent. When the starting roller is engaged by the detent, one of the flat surfaces will always be opposite the platen, and, therefore, spaced therefrom and out of engagement with the strips. The contacting surface extending between these notches is of sufficient length to feed the strip to that point where the feed rollers will again engage the strips in one-half revolution of the starter roller.

A transverse plate 56, having a dependent flange 56a, is secured between the free ends of the arms 34 as shown in Fig. 3 and riveted in place. This plate is positioned so as to be parallel with the rod 33 and carries the detent mechanism for restraining rotation of the starter roller.

An L-shaped bracket 57 is secured to the transverse plate and a detent 58 is mounted thereon so as to extend into engagement with the notches on the contacting surfaces, herein shown as engaging only the surface 45a. The detent is provided with an opening 59 to receive a pivot pin 60 carried by the bracket. The opening is larger than the pin so that the detent is capable of slight bodily movement as well as pivotal movement about the pin. An L-shaped spring 61 has one end secured to the bracket 57 and the other end secured in a slot 62 on the detent and normally holds the detent in down position with the pivot pin at the front end of the opening 59 as shown in Fig. 8. A driving opening 63 is provided in the detent to receive the actuator for moving it from engagement with the starter roller and to release position.

The actuator comprises a mechanism which includes a pair of arms 65 and 66 spaced 180° apart and laterally displaced on a hub 67. The hub is pivotally mounted on the transverse plate 56 by a screw 68. The free end of the arm 65 extends into the opening 63 to actuate the detent. As shown in Figs. 1 and 3, the arm 65 extends through the opening in the detent and into a horizontal slot 78 in bracket 57 which forms a bearing for that end of the lever and guides it in its movement.

The free end of the arm 66 is pivoted to the end of a lever 69 of a T-shaped lever 70 which is also pivoted to the transverse plate by a screw 71. Another lever 72 of the T-shaped lever extends into a position to be engaged by a trip device. The third lever 73 of the T-shaped lever is slotted at 74 to receive a leaf spring 75 secured to a stud 76 on the transverse plate.

The spring biases the actuator to a position in which the detent engages the starter roller and the lever 72 is in position to be actuated by the trip device. A stop pin 77, mounted on plate

56 and engaging lever 69, limits movement of the actuator under influence of spring 75 and determines these positions.

The actuator for releasing the detent can be operated in many ways to release the starter roller when it is desired to again render the feeding means operative.

In the present preferred form of the invention, the detent is released, through the control of a suitable feeler mechanism which engages the paper, in response to cessation of the advance of the paper during feeding operations of the platen. This will insure that the starting means will not be operated during the normal intermittent operation of the advancing means, but will operate only at form-length intervals when the feeding means is inoperative to feed the strip.

This control is accomplished in the form of the invention shown in Figs. 1 and 2 by having the feed roller 32b formed with an outwardly extending hub 80 provided along its edge with a plurality of camming surfaces 81. In the preferred form of the invention, the cams are spaced around the hub at line space intervals.

A feeler sleeve 82 is loosely mounted on the stationary rod 33 and extends into a recess 83 formed in the end of the hub. The sleeve is provided at one end with a projection 82a carrying a soft rubber roller 84 which is adapted to engage the strip and be driven thereby so as to rotate the sleeve when the strip is advanced. A trip device, having a sleeve 85 with an integral collar 86, is mounted to slide longitudinally of the sleeve 82 with the end of the sleeve 85 also entering the recess in the hub. The sleeve 85 is provided with a cam follower 87 which is held in engagement with the cams by means of a spring 88 interposed between the collar 86 of the trip device and the projection 82a on the end of the feeler sleeve. The cam follower has a projection 89 which extends into a slot 90 formed in the feeler sleeve to prevent relative rotation of the trip device on the sleeve while permitting longitudinal sliding action therealong. A pair of collars 91, 92, secured to the rod 33 by set screws, hold the assembly in adjusted position on the rod.

The collar of the trip device is provided with a serrated edge 93 which is adapted to positively engage the lever 72 of the actuating mechanism when the follower rides up on the camming surfaces. The follower, as shown in Figs. 3 and 4, is provided with a flat side 87a which enables it to quickly move into deep position with respect to the camming surface after the trip device has moved the actuator to release the detent from the starter roller.

Inasmuch as the position of the rod 33 carrying the feed rollers and the feeler roller is determined by the feed rollers, the feeler roller must be able to shift to accommodate for movement of the bar when it enters the notches in the paper and again when it raises out of the notches to run on the surface of the paper.

As is shown in Fig. 3, the sleeve 82 carrying the feeler roller has a slightly enlarged bore 82b to permit it to move vertically relative to the rod 33. This enables the feeler roller to at all times engage the paper to be driven thereby.

The soft rubber of the feeler roller also assists in maintaining the drive between the paper and feeler roller for slight movements of the rod.

In operation, the detent 58 normally engages the notch in the starter roller and prevents it from rotating with the sleeve 47 and its connected feed roller (Fig. 6). The actuating mech-

anism for the detent is inoperative to release the latter during normal advancing of the strip. The feed rollers will advance the strip line-by-line and the feeler roller, which is driven by the advancing paper, will, of course, rotate simultaneously with the feed roller.

When the feed roller engages the feed-arresting notch in the paper, the strip will not be advanced even though the feed rollers are rotated by the feeding means. The feeler roller, being driven by the paper, will not rotate. Further operations of the feeding means, while in inoperative advancing relation with the strip, will cause the feed rollers to rotate while the feeler roller remains stationary.

According to the present invention, the relative rotation between these elements is used to release the starting mechanism. During the initial rotation of the feed roller 32b in inoperative advancing relation with the strip, the hub 80, rotated thereby, will cause the cam formed thereon to rotate with respect to the follower on the sleeve which is held against rotation by the feeler roller engaging the stationary strip. The cam will shift the trip device against the action of the spring 88 and into engagement with lever 72 of the actuating mechanism for the detent. Movement of the arm 72 to the right, as shown in Figs. 3 and 4, will cause the lever arm 65 to engage the front edge of the opening 63 and raise the detent about the pivot 66, out of engagement with the notch, so that further operations of the feeding means will cause the starter roller to be rotated and engage the strips to advance them as shown in Fig. 8.

As shown in Fig. 7, the detent, upon being released, is also bodily moved forward and held in this position so that it cannot engage the notch in the starter roller until the latter has completed a half turn.

The starter roller is now free to turn with sleeve 47 and continued operations of the feeding mechanism will cause the starter roller to move the paper a sufficient distance to remove the stopping apertures from under the feed rollers whereupon the feed rollers again resume feed of the strip until the next set of stopping apertures are positioned under the feeding rollers.

It will be seen that the starter mechanism is automatically thrown into action, by a predetermined operation of the feeding mechanism after it has been made inoperative to advance the strips, to restart the feed of the strips without an operator being present.

In some instances, the pressure of the feeler roller resting on the paper, at it passes over the platen, may be sufficient to advance the strips with the platen even though the feed rollers are disposed in the notches in the form. In the form of the invention shown in Figs. 9 and 10, this difficulty is avoided by disposing the feeler roller so that it engages the paper to be driven thereby at a point remote from the platen.

In this form of the invention, an arm 95 is disposed between the collar 92 and the projection 82a on the end of the sleeve 82. The arm is pivotally mounted on the rod and has at its outer end a rubber-covered feeler roller 84' rotatably mounted. The arm will carry the feeler roller so that it engages the advancing strips and is rotated thereby. The feeler roller has a gear 96 secured thereto. The projection 82a on the sleeve 82 has a gear 97 secured thereto and is geared through an intermediate gear 98 carried by the arm to the feeler roller to be rotated

thereby. The feeler roller will now engage the paper at a point spaced from the platen and will be driven by the advancing paper which, through the gearing arrangement, will rotate the sleeve 82 as the paper is advanced. The gearing is such that the sleeve 82 will be rotated in unison with the feed rollers during an advancing operation.

When the feed rollers engage the notches so that the advance of the paper is arrested, the feeler roller will no longer be driven. Continued operation of the feed rollers in inoperative advancing position will cause relative movement between the hub 80 and sleeve 82 and associated elements, whereby the trip device will be operated to release the detent from the notch in the starter roller as in the previously described form of the invention to automatically render the feed means operative again to feed the strips.

In order to insure that the feeler roller will be driven by the paper, a supporting roller 99 is mounted on a rod 100 on a projection of the arms 34 so as to be disposed beneath the paper. The weight of the pivoted arm will cause the feeler roller to engage the paper and press it against the supporting roller. This will insure a satisfactory driving engagement between the strip and the feeler roller.

Variations and modifications may be made within the scope of this invention and portions of the improvements may be used without others.

I claim:

1. In a manifolding device having a platen over which a continuous strip is advanced; intermittently operating feeding means coacting with the strip to advance the strip line-by-line, said means becoming temporarily ineffective to continue to advance the strip after the strip has advanced a predetermined amount, and means automatically made operative for causing said feeding means to resume strip advancement after predetermined ineffective operations of said feeding means.

2. In a manifolding device having a platen over which a strip is advanced; feeding means for advancing the strip a predetermined length, said feeding means becoming temporarily ineffective to continue to advance the strip after the strip has advanced said predetermined length; and means automatically made operative by continued operation of the feeding means after the same has become ineffective to advance said strip for causing the feeding means to again become effective for strip advancement.

3. In a manifolding device having a platen over which a strip is advanced; intermittently operating feeding means for advancing the strip line-by-line, said feeding means becoming ineffective to continue advancement of the strip after the strip has advanced a predetermined amount; a feeler mechanism engaging the strip so as to be moved by the advancement of the strip; and means for causing the feeding means to again become effective for strip advancement after a number of ineffective operations of the feeding means, said last-named means being controlled by the action of the feeler mechanism.

4. In a manifolding machine having an intermittently operated platen over which a strip having apertures therein is advanced line-by-line; feeding means for advancing the strip comprising feed rollers operative upon the material of the strip to effect feed and which, upon engaging apertures in the strip, become inoperative to continue advancement; a feeler mechanism including a feeler roller adapted to engage the strip and be rotated

by the advancement of the strip; strip-starting means for again making the feeding means operative for strip advancement; and means for rendering the starting means operative, said means being actuated by the differential movement between the feeler mechanism and the feed rollers during a predetermined number of operations of the feeding means, when the latter is in inoperative advancing relation with the strip.

5. In a manifolding machine having an intermittently operated platen over which a plurality of strips having feed-arresting, form-registering apertures therein are advanced line-by-line; feeding means for advancing the strips, comprising means operative upon the material of the strip to effect feed and which, upon engaging the apertures in the strips, becomes inoperative to continue the advancement; strip-starting means for again making the feeding means operative for strip advancement; and means for causing the starting means to become operative during a predetermined number of operations of said feeding means when the latter is in inoperative advancing relation with the strip.

6. In a manifolding machine having a platen over which a strip is advanced; feeding means for advancing the strip a predetermined length, said feeding means becoming temporarily ineffective to continue to advance the strip after the strip has been advanced a predetermined length; starting means for causing the feeding means to again become effective for strip advancement; and means initiated by relative movement between the advancing means and the nonadvancing strip for rendering said starting means operative.

7. In a manifolding machine having a platen over which a strip is advanced; feeding means for advancing the strip a predetermined length, said means becoming temporarily ineffective to continue the advance of the strip after the strip has advanced said predetermined length; means for causing the feeding means to again become effective for strip advancement, including a trip device; and means operated by a differential movement between the advancing means and the strip for actuating said trip device.

8. In a manifolding device having a platen over which a strip is advanced; feeding means for advancing the strip a predetermined length, said means becoming temporarily ineffective to continue the advance of the strip after the strip has advanced said predetermined length; a mechanism engaging the strip to be moved by the advancement of the strip; and means automatically made operative as an incident to cessation of the movement of said strip for causing the feeding means to again become effective for strip advancement, said last-named means being actuated by the differential movement between the mechanism engaging the strip and the feeding means during a predetermined number of ineffective operations of the feeding means.

9. In a manifolding device having a platen over which a plurality of superposed strips are advanced; feeding means for advancing the strips a predetermined length, said feeding means becoming temporarily ineffective to continue advancement of the strips after the strips have advanced a predetermined length; a feeler mechanism engaging the strips to be moved thereby; and means automatically made operative as an incident to cessation of movement of the strips for moving the feeding means to again become operative for strip advancement, said last-named means being actuated by a differ-

tial movement between the feeler mechanism and the feeding means during a predetermined movement of operations of the feeding means when the latter is in ineffective advancing relation with the strips.

10. In a manifolding machine having a platen over which a strip having apertures therein is advanced; feeding means for advancing the strip, comprising means operative upon the material of the strip to effect feed and which, upon engaging in the apertures in the strip, becomes inoperative to continue the advancement; strip-starting means for again making the feeding means operative for advancement; and means operated during cessation of movement of the strip and incident to the continued operation of the feeding means for rendering the starting means operative.

11. In a manifolding machine having a platen over which a strip having apertures therein is advanced; feeding means for advancing the strip, comprising means operative upon the material of the strip to effect feed and which, upon engaging in the apertures in the strip, becomes inoperative to continue the advancement; a starting mechanism normally urged to feed the strip but held against feeding movement; and means for releasing the starting mechanism as an incident to cessation of advancement of the strip and continued operation of the feeding means.

12. In a manifolding machine having a platen over which a plurality of superposed strips having feed-arresting, form-registering apertures therein are advanced; feeding means for advancing the strips, comprising means operative upon the material of the strip to effect feed and which, upon engaging in the apertures in the strips, becomes inoperative to continue the advancement; starting mechanism for causing the feeding means to again become operative to advance the strips; and means automatically controlled by movement of the strips and incident to the cessation of the same and continued operation of the feeding means for causing the starting means to be rendered operative.

13. In a manifolding machine having a platen over which a plurality of superposed strips having feed-arresting, form-registering apertures therein are advanced; feed rollers cooperating with the platen to operate on the material of the strips for advancing the strips; the advancing means becoming inoperative to continue the advancement of the strips when the feed rollers engage in the apertures in the strips; a feeler mechanism contacting the strips to be moved by advancement of the strips; a starter mechanism for again making the advancing means operative to feed the strips; and means operated in response to relative movement between the feed rollers and the feeler mechanism for rendering the starter mechanism operative.

14. In a manifolding machine having a platen over which a plurality of superposed strips having feed-arresting, form-registering apertures therein are advanced; feeding means for advancing the strips, comprising means operative upon the material of the strip to effect feed and which, upon engaging in the apertures in the strips, becomes inoperative to continue the advancement; a starting roller; a trip device for retaining the starting roller from feeding the strips; and means operable automatically during cessation of movement of the strips and incident to continued operation of the feeding means for

causing the trip means to be released and the starting roller to become operative to move the strips whereby the feeding means again engages the strips and becomes operative.

15. In a manifolding machine having a platen over which a strip having apertures therein is advanced; feeding rollers cooperating with the platen to operate on the material of the strips for advancing the strip, the advancing means becoming inoperative to continue the advancement of the strip when the feed rollers engage in the apertures in the strip; a feeler mechanism including a feeler roller contacting the strip to be moved by advancement of the strip and therefore be simultaneously rotated with the feed roller during strip advancement; a starter mechanism; means for holding the starter mechanism inoperative; and means interposed between the feed roller and feeler roller and adapted to be moved incident to relative movement therebetween due to rotation of the feeding means while the feeding means is engaged in the apertures to release the holding means for the starter mechanism.

25. 16. In a manifolding machine having a platen over which a strip having apertures therein is advanced; feed rollers cooperating with the platen and operative upon the material of the strip for advancing the strip until engaged in the apertures in the strip, one of said feed rollers having a hub thereon; means for supporting said feed rollers; a feeler mechanism mounted on the feed roller support and comprising a feeler roller contacting the strip to be moved by advancement of the strip and a sleeve rotated by said feeler roller and extending into cooperative relation with the hub on the feed roller; a trip mechanism carried by the sleeve and adapted to be moved by the hub upon relative rotation between the sleeve and the hub; a starter mechanism for again making the advancing means operative to feed strips; and detent means for holding the starter mechanism in inoperative position, the cessation of feeding of the strip during continued operation of said feed rollers causing relative movement between the hub and sleeve, thereby actuating the trip mechanism into a position wherein it engages and moves the detent means to release the starter mechanism.

35. 17. In a manifolding machine having a platen over which a plurality of superposed strips having apertures therein are advanced; feed rollers cooperating with the platen and operative upon the material of the strips for advancing the strips until engaged in the apertures in the strips, one of said feed rollers having a hub thereon; means for supporting said feed rollers; a feeler mechanism mounted on the feed roller support and comprising a feeler roller mounted to rotate on the support means adjacent the platen and having a sleeve secured thereto and extending into cooperative relation with the hub on the feeler roller; a trip mechanism carried by the sleeve for relative longitudinal sliding movement and adapted to be urged into engagement with the hub; means mounted on the hub and engaging the trip mechanism to move the same laterally of the sleeve upon relative rotation between the sleeve and the hub; a starter mechanism for again making the advancing means operative to feed strips; and means for holding the starter mechanism in inoperative position, the cessation of feeding of the strip during continued operation of said feed rollers causing relative movement between the hub and

the sleeve, whereby the trip mechanism is actuated into a position wherein it engages and moves the holding means into release position.

18. In a manifolding machine having a platen over which a plurality of superposed strips having feed-arresting apertures therein are advanced; feed rollers cooperating with the platen and operative upon the material of the strips for advancing the strips until engaged in the apertures in the strips, one of said feed rollers having a hub thereon; means for supporting the feed rollers in operative relation with the platen, a feeler mechanism mounted on the feed roller support and comprising a feeler roller contacting the strips in spaced relation to the platen to be moved by advancement of the strips, and a sleeve operatively connected to be rotated by said feeler roller and extending into cooperative relation with the hub on the feed roller; a trip mechanism carried by the sleeve and adapted to be moved by the hub upon relative rotation between the sleeve and the hub; a starter mechanism for again making the advancing means operative to feed strips; and detent means for holding the starter mechanism in inoperative position, the continued operation of the feed rollers during the period that it is in inoperative relation with the strips causing relative movement between the hub and sleeve, thereby actuating the trip mechanism into a position wherein it engages and moves the detent means into release position.

19. In a manifolding machine having a platen over which a plurality of superposed strips having feed-arresting, form-registering apertures therein are advanced; feeding means including feed rollers and operative upon the material of the strips for advancing the strips until engaged in the apertures in the strips, one of said feed rollers having a hub thereon; means for supporting said feed rollers in cooperative relation with the platen; a feeler mechanism mounted on the feed roller support comprising an arm carrying a feeler roller in spaced relation to the platen and contacting the strips so as to be rotated by advancement of the strips, a sleeve rotatably mounted on the feed roller support and extending into cooperative relation with the hub on the feed roller, and means carried by the arm for connecting the sleeve to the feeler roller to be rotated thereby; a trip mechanism carried by the sleeve and adapted to be moved by the hub upon relative rotation between the sleeve and the hub; a starter mechanism for again making the advancing means operative to feed strips; and detent means for holding the starter mechanism in inoperative position, the continued operation of the feed rollers during the period that it is in inoperative relation with the strips, causing relative movement between the hub and sleeve, thereby actuating the trip mechanism into a position wherein it engages and moves the detent means into release position.

20. In a manifolding device having a platen over which a strip is advanced; intermittently

operating means for advancing the strip line-by-line a predetermined distance at the limit of which the feeding means becomes ineffective to further advance the strip and movement of the strip ceases; and means automatically made operative after a predetermined number of ineffective operations of said feeding means for causing the feeding means to again become effective for strip advancement.

10 21. In a manifolding device having a platen over which a strip is advanced; intermittently operating means for advancing the strip line-by-line, said means cooperating with the strip and becoming temporarily ineffective to advance the strip after the strip has advanced a predetermined distance; and means to automatically cause the feeding means to again become operative for strip advancement after a predetermined number of ineffective operations of the feeding means.

20 22. In a manifolding device having a platen over which a strip having spaced physical alterations therein is advanced; intermittently operating means cooperating with the strip for advancing the strip line-by-line, said means coacting with said physical alterations and becoming temporarily ineffective to advance the strip after the strip has advanced a sufficient distance to cause the next spaced alteration to move into cooperative relation therewith; and means for automatically causing the feeding means to again become effective for strip advancement after a predetermined number of ineffective operations of the feeding means.

25 23. In a manifolding device having a platen over which a strip is advanced; intermittently operating means for advancing the strip line-by-line, said means cooperating with said strip and becoming temporarily ineffective to advance the strip after the strip has advanced a predetermined distance; and means automatically made operative as an incident to cessation of movement of the strip and a predetermined number of operations of the feeding means while in ineffectual feeding relation with the strip for causing the feeding means to again become effective for strip advancement.

30 24. In a manifolding device having a platen over which a strip having spaced physical alterations is advanced; intermittently operating means for advancing the strip line-by-line, said means coacting with said alterations and rendering the feeding means temporarily ineffective to advance the strip after the strip has advanced a distance sufficient to cause the next spaced alteration to be moved into cooperative relation with said means; and means automatically made operative as an incident to the cessation of movement of the strip and a predetermined number of ineffectual operations of the feeding means for causing the feeding means to again become effective for strip advancement.

ARTHUR A. JOHNSON.
